UNITED STATES PATENT OFFICE.

RICHARD VARLEY, OF ENGLEWOOD, NEW JERSEY.

ELECTRICAL SYSTEM.

1,081,413.

Specification of Letters Patent. Patented Dec. 16, 1913.

Application filed June 16, 1913. Serial No. 773,807.

To all whom it may concern:

Be it known that I, RICHARD VARLEY, a citizen of the United States of America, residing at Englewood, in the county of 5 Bergen and State of New Jersey, have invented new and useful Improvements in Electrical Systems, of which the following is a full, clear, and exact description, reference being had to the accompanying drawings, which form part of this specification.

This invention relates to electrical systems. It may find embodiment in many systems wherein it is desired to create a high tension and effectively sustained intermittent flow of current or electrical discharge at a current using instrumentality. In the particular instance I have selected as an embodiment of my invention an ignition system whereby the combustible 20 charges of an engine may be exploded.

The usual ignition system employing a coil or generator inductively wound produces a high voltage spark of short duration and low heat, and therefore, poor ignitive value. This is due to the radical magnetizing and demagnetizing effect upon the core or armature of the inductive generator, upon breaking of the primary circuit, and resultant non-sustained magnetic 25 flux action; the momentarily induced current in the secondary winding producing a correspondingly short ineffective spark, and while in the alternating current high tension magneto or generator there is a certain amount of current augmentatively generatedly impressed upon the secondary 30 winding of the armature by reason of its rotation, after the primary circuit has been interrupted, its amperage is so slight that it is practically impotent. It is also commonly known that in the usual ignition system, self-induction and reactance in the interrupted primary winding, causes flashing or 35 sparking at the interrupter contacts which necessitates the employment of the more expensive, precious and less readily oxidizable metals, such as platinum and iridium, for contact service, and also requires a condenser or other spark arresting means connected across said contacts for the absorption of such extra or self-induced current, as a protection to the contacts.

The general object of my invention is to 50 provide a system whereby there may be readily formed a spark having the charac-

ter substantially of arc-sustenance and high heat value as contradistinguished from the instantaneously delivered low heat spark above referred to, thereby producing a 60 spark operatively alive for a greater period of time relatively to the travel of the piston, than heretofore has been possible and thus making it effective upon thin or weak gas mixtures and such charges as contain occluded dead or weak spots. Furthermore I provide a system in which I may dispense with the condenser or other spark arresting means.

A further object of my invention is to 70 provide a system which may be used in connection with the usual lighting generator in such manner as to render the use of a separate ignition magneto unnecessary.

My invention comprises, broadly, a 75 source of current, a transformer in association with a current using instrumentality, such as a spark plug, and means for so controlling the transformer with respect to the source of current as to cause operative prolonged energizing of the current using instrument, as will be hereinafter more fully described.

Figure 1 is a diagrammatic view of circuits and apparatus embodying my invention, said diagram showing a particular electrical system, such as may be used in connection with automobile equipment, and to be hereinafter more fully referred to; Fig. 2 is a diagrammatic view of a modification of my system; Fig. 3 is a similar view, showing a condenser connected across interrupter contacts; Fig. 4 is another diagrammatic view showing a modified form of spark plug connection; Fig. 4^a is a fragmentary side elevational view of the spark plug employed in the system disclosed in Fig. 4; and Fig. 5 is a view corresponding with Fig. 1 but showing an auxiliary ignition circuit associated therewith, all views to be 100 hereinafter more fully described.

In Figs. 1 and 5 I show my invention in association with a particular form of generator capable of delivering both continuous and alternating current, the former for supplying a work or light circuit (as that of an automobile system) and the latter for energizing an ignition circuit or other current using circuit. This duplex generator forms subject matter of my invention disclosed in application Serial No. 704,259, filed June 17, 1912, and used in connection with

this description because of incidental advantageous current wave characteristics thereof, as hereinafter more fully described.

Referring to Fig. 1, the generator 2 comprises an armature 3, preferably drum wound, mounted upon a shaft 4 and provided with a commutator 5 and slip rings 6, whereby the generator, in accordance with my invention disclosed in the above mentioned application, is adapted to furnish both continuous and alternating current. The generator is provided with a shunt field winding 7 and a series field winding 8 that are connected to oppose each other. Lamps 9 are in circuit with the generator, a storage battery 10 and the series field winding 8. The lamp circuit is supplied from the storage battery until such time as the generator reaches a suitable predetermined degree of voltage after which the continuous current is supplied from the armature 3 which also begins to charge the battery. To effect this control of the continuous current circuit I provide a magnetic cut-out or relay comprising a core 11 having winding in circuit with field winding of the generator and consisting, preferably, of a shunt coil 12 and a series coil 13 which have a common terminal contact connection 14 with which contact is adapted to contact a contact member 15 carried by and electrically connected to a pivotally mounted armature 16 connected in the continuous current circuit and normally held out of contactual engagement or from the core 11 by a suitable spring 17.

A transformer core 18 which may be of any suitable shape or construction, carries upon one leg 19 thereof a coil 20 that receives, upon driving of the armature 3, alternating current from the generator 2 through the collector slip rings 6. Upon another leg 21 of the transformer core is a second winding or choke coil 22 having a small number of turns and a secondary winding or a coil 23 having a larger number of turns of relatively smaller wire, one terminal of each coil preferably being grounded, as shown. In the circuit of the coil 22 is an interrupter 24 comprising a stationary contact member 25, a movable contact member or lever 26 and an actuating cam 27. The cam 27 may be operatively associated with the armature shaft 4 or may be driven by any suitable device having a proper speed ratio with the engine shaft (not shown).

The secondary coil 23 is connected to a distributor 28, more particularly to the rotatable arm 29 thereof that co-operates contactually with members 30 which connect to the usual spark plugs 31 of a combustion engine. Proper synchronizing of the distributor with the circuit interrupting means 65 may be effected in any suitable manner,

such as by gearing 32, as is well understood, and the interrupter cam 27 is of such shape and so arranged as to cause commensurate opening and closing of the circuit of the coil 22 at a suitable point or points 70 in the alternating current wave, as hereinafter described.

It will be understood that the generator 2 may be driven by the engine through any suitable form of gearing or connection (not shown) so as to energize the alternating current circuit. Although I am not limited to the use of a generator in which any given number of pulsations or alternations of the current take place in each revolution of the armature, for automobile systems I may employ a type of machine of such construction and so arranged that two alterations of the generator current occur during each revolution of the armature 3. The coil 20 of the alternating current circuit will be correspondingly symmetrically energized, setting up a magnetic flux in the transformer core 18. Normally the circuit of the coil 22 is closed by the interrupter 24 so that said coil effectually acts as a choke upon the travel of the magnetic lines of force set up in the transformer core, causing a repression thereof from that particular portion of the core and maintenance of a state of flux in the remainder of the core. Rotation of the cam 27, causes sudden opening of the circuit of said coil 22 at a suitable point in the current wave. This point of opening of the circuit may take place, by reason of synchronous relationship of the cam and the generator, at or near the maximum point or period of the wave. Opening of the coil 22, as stated, causes a disruptive discharge of current of high voltage to take place in the secondary coil 23 in circuit with which is the current using apparatus or spark producing means above described. Repression of the flux by short circuiting of the coil 22 causes the magnetic lines of force to assume an abnormal path. The abnormal path taken is preferably a magnetically reluctant one, as by employing a core, such as shown, in which the flux takes a leakage path across an air gap or space intermediate the sides of the transformer. When the coil 22 is open, the diverted repressed flux takes the less resistant magnetic path provided by the core, causing in the leg 21 thereof a magnetic surge of great intensity by reason of its restoration to normal and change of path of travel. The voltage is immediately generatively built up in the secondary coil 23 sufficiently to instantly bridge or break down the air gap between the electrodes or terminals of the respective spark plug. However, the spark thus formed is not a mere instantaneous flash or of brief duration but it continues to burn in the form substantially of a flaming arc, for the break-

125
130

ing down of the normal reluctance of the spark gap and inauguration of the spark or arc in effect causes a closing of the circuit containing the coil 23 with the result that 5 there is established a mutual or reciprocal regulative relationship between the arc and the coil 23 or the flow of flux, which tends to prevent immediate equalization of the flux or demagnetization or dissipation of the 10 energy of the transformer and serves to greatly prolong or extend the time or the life of the arc. In other words, as the arc is established, current flows in the secondary circuit or the circuit of the coil 23 and the 15 ampere turns of the secondary coil 23 take the place, in their effect, of that of the coil 22, thus tending to again choke or restrain the inflow of flux and preventing an abruptive or instantaneous exhaustive discharge of 20 energy at high voltage. This choking effect is controlled by the arc which assumes, by reason of its establishment in the circuit of the coil 23, a rheostatic function, for the voltage of the arc itself is sustained by the 25 flux change, which flux change is, in turn, controlled by the arc amperage. Therefore, with a resident body of flux in the core, preferably partially sustained by the active source, increase of arc resistance decreases 30 the arc amperage, allowing increase of flux and so reciprocal increase of arc voltage, thus tending to maintenance of arc stability and affording an arc that is operative upon poorly mixed or thin charges of gas or gas 35 charges of low volatility.

My construction combines the advantages of such systems as operate to induce a spark by breaking of the primary circuit and of systems in which the spark is produced by 40 closing of the primary circuit. In addition, my system operates to instantaneously break down the resistance of the spark gap with a current of high voltage and to follow the initial formation of the spark with a current 45 of sustained high heat value.

The instantaneous establishment of the spark at the plug and its maintained utilization of energy, causes the active secondary circuit containing the spark producing 50 means, to so absorb the energy and control the flux action as to prevent self-inductance of a sparking current in the circuit containing the interrupter contacts. As a result, there is little or no tendency to 55 sparking between the interrupter contacts upon opening of the circuit of the coil 22. I am thus enabled to employ ordinary material, such as copper, for the above parts, and to dispense with the use of a condenser 60 or other spark arresting means which is necessary in the ordinary systems to absorb the sparking resulting from interruption of a primary circuit.

As the generator speed increases after 65 starting, the voltage reaches a predeter-

mined value at which the cutout coils 12 and 13 are sufficiently energized to attract the armature 16 in such manner as to effect engagement of the contact members 14 and 15. The generator now charges the battery 70 10 and supplies current to the lamps 9. The charging circuit remains closed so long as the generator voltage exceeds that of the battery. When the generator voltage drops below battery charging value, current flows 75 from the battery in a reverse direction through the series coil 13 and the latter then opposing the coil 12, reduces the magnetic attraction and thus releases the armature 16, breaking the battery charging circuit. As above stated, the lamps may be supplied with current from the battery 10 when the generator voltage is below the predetermined value. The lamps may be controlled individually by switches 33 or 80 collectively by a switch 34 and a usual plug switch 35 may be included in the circuit of the coil 20 to control the ignition circuit. 85

By employing a drum wound armature, as incident to its service in a lighting generator, I produce a current wave that is substantially a true sine curve characteristic of which is its broad or long sustained peak or maximum period of flow. This enables me to produce in the transformer a prolonged flux action of correspondingly effective value in systems where the coil 22 is brought out of closed circuit at or near the peak of the wave. However, it will be understood that I do not desire to limit myself to a system in which any particular mathematical relationship obtains between the interrupter mechanism and the generator phases or current wave. 100

A modification of my invention is illustrated in Fig. 2 in which like numerals are used to designate the corresponding parts. In the ignition system here shown, only one collector ring 6 is employed, one terminal of the armature winding being grounded in 110 circuit with the grounded end of the coil 20. The operation of this system is the same as that disclosed in Fig. 1 and a full repeated explanation is unnecessary to a complete understanding of the same. 115

A second modification of my invention is shown in Fig. 3 and differs from the preferred form shown in Fig. 1 in that a condenser 37 is connected across the interrupter terminals. In the use of my invention in 120 its preferred form, the condenser is omitted, but it may be employed if desired. Its employment may be necessary where abnormal conditions obtain in the circuits, and it will be understood that I do not desire to limit 125 my invention either to the use or the omission of a condenser.

In Fig. 4 I show another modification the illustrated parts of which correspond with those shown in Fig. 1, and accordingly bear 130

like reference numerals, with the exception of the spark plugs and connections in the secondary circuit of the coil 23. In this view I show a spark plug 38 carrying an insulated electrode 39 coacting with which is a movable electrode or flier 40 synchronously geared to the interrupter cam 27. For convenience of illustration I show only two spark plugs with a uniform ratio of 10 driving connections between the fliers and interrupter cam. The timing relationship is such as to bring the movable electrodes or fliers consecutively into and out of spark establishing relationship with the respective 15 stationary electrodes 39, (as would be the case with a two cylinder two cycle engine). It will be seen that this type of plug presents a terminal which may utilize my peculiar sustained form of current to great 20 advantage. The insulated electrode 39 in each case connects with the secondary coil 23 and each movable electrode is grounded. The latter electrode 40 preferably has an extended spark establishing surface formed 25 substantially concentric with its pivotal stem or mounting so that the spark gap between the electrodes remains practically constant while the operative face of the movable electrode is passing the stationary electrode. When the movable electrode approaches the stationary electrode sufficiently to form a normal spark gap and upon opening of the coil 22, the reluctance of said gap is immediately overcome or broken down by 30 the high tension current which establishes a spark. As stated above, the spark is formed at a high electromotive force and is maintained at high heat value. As the spark continues to burn, it is caused, by 35 travel of the movable electrode, to be extended or drawn out between the stationary electrode and the point of initiation of the spark on the movable electrode to a greater length than the normal distance between the 40 electrodes, thus sustaining the spark for its operative period in an increased arc-like manner which greatly augments its ignitive effect. As the resistance of this arc increases the spark or flame seeks another 45 point on the operative face of the movable electrode so long as the latter remains in normal spark gap relationship with the stationary electrode, for the reason that the normal reluctance of the gap has been 50 broken down in the setting up of the spark and it continues to be fed or kept alive by the active coil 23 even though certain points between which the arc is maintained may shift. The spark is therefore carried 55 through space until the movable electrode passes from the other. Shifting of the spark in this manner renders it exceedingly effective upon charges of gas which are not highly volatile, or thin mixtures, or upon such 60 charges as carry contained or occluded dead 65

spots. Furthermore, by the employment of plugs such as shown, it is unnecessary to use the usual current distributor, as the plugs themselves may constitute the distributing agent whereby proper apportioning of the 70 current to the plugs is effected. In other words, as the movable electrodes are synchronously geared to the interrupter mechanism, it will be seen that no firing can take place until the respective movable electrode 75 is swung into spark establishing position. The movable electrode, as shown in Figs. 4 and 4^a may carry gas agitating blades 41 which, upon movement of the electrode, serve to disturb the gas charges at points 80 adjacent the electrodes so as to dissipate any dead pockets or inactive particles which frequently form at the heated spark plug, thus rendering ignition more effective.

From the foregoing it will be understood 85 that in order to energize the transformer and produce an ignition current it is necessary to drive the armature 3 at a generative speed.

In Fig. 5 I show a modified form of my 90 invention, wherein means are provided for setting up an initial energizing of the transformer prior to such time as the generator 2 may furnish an effective current, or at such times when it is desired to run on battery 95 ignition independently of the lighting generator. In this view, I show generally a system corresponding with that disclosed in Fig. 1 with the exception that circuit and switch means are provided for setting up 100 from a battery circuit, inductive energizing of the coil 23, as by the battery 10. On the leg 21 of the transformer I place, in addition to the coils 22 and 23 above described, a coil 42 in the circuit of which is a portion of 105 the coil 20 and a trembler or buzzer 43. A double armed switch 44 controls connection of the coil 20 with the generator and the coil 42 with the battery. Arranged in juxtaposition to the cut-out armature 16 is a contact 110 member 45 which normally, by reason of the spring 17, coacts to establish a battery circuit through the coil 42 and a portion of the coil 20. With the double armed switch shifted to connect, through a switch contact 115 46, the circuit containing the coil 42, the current flow from the battery will be through vibrator 43, coil 42, a portion of the coil 20 and through the generator back to the battery. In the particular diagram shown this 120 circuit through the generator is illustrated as being established from one of the slip rings 6; through the armature winding and the series field winding 8; the alternating current circuit being broken by disconnection of the lead connecting with the other slip ring and opposite terminal of the coil 20. Energizing of the coil 42 and a portion 125 of the coil 20, induces a magnetic flux in the transformer core 18, which seeks the 130

normal magnetic path of the core. As the active turns of winding of the coil 20 and the coil 42 are unidirectionally wound the lines of force set up respectively by these 5 two coils, tend to meet one another in opposition at an intermediate point in the core. With the choke coil 22 short circuited by the interrupter mechanism the flux of the leg 21 is forced back or repressed against that in 10 the opposite end of the transformer core, so that it is compelled to seek an abnormal path the same as with the alternating flux above described. Opening of the choke coil 22 permits the trembled current to flow 15 through the coils 20 and 42, by means of the active buzzer 43, producing a high tension current in the secondary winding 23 for ignition service. After starting of the engine on battery current and when the generator 20 is being driven at a speed productive of effective ignition current, the double armed switch 44 may be shifted to the dotted position shown, thus breaking the battery circuit and establishing the alternating current 25 circuit of the coil 20. Such breaking of the battery circuit leaves the coil 42 in an open circuit condition so that it has no effect upon the transformer or the windings carried thereby while the generator is delivering current to the coil 20 in the alternating 30 current circuit. Where, as through neglect of the operator, the double armed switch has not been shifted to break the battery circuit, building up of the generator voltage to battery 35 charging strength will cause a closing of the cut-out armature 16, thereby bringing said armature out of contactual engagement with the contact member 43 and thus automatically breaking the battery circuit. Resultant 40 interruption of the continuity of firing or spluttering of the engine, operates as a signal for the operator to shift the switch to alternating current connection. However, the double armed switch may be 45 electrically controlled, as by a spring pressed solenoid subject to voltage or current variation of the generator 2, so that when the generator reaches a speed capable of operatively energizing the coil 20, the solenoid 50 will immediately cut out the continuous current circuit or, upon dropping of the generator current to an ineffective value, will open the alternating current circuit and establish the continuous or battery ignition 55 circuit. Where it is desired to run the engine on battery ignition for any extended time, the switch 44 may be shifted to bring the continuous current circuit arm thereof to the contact piece 47 which grounds a portion 60 of the coil 20 and the coil 42 and the vibrator 43 into circuit with the terminal of the battery grounded in common, as at 48, with the circuit of the lamps 9. With the establishment of such circuit connections the 65 transformer operates in the same manner as

previously described in connection with the other continuous current circuit connection.

The advantages of my invention reside in the provision of means whereby there can be obtained a spark of substantially flaming arc-like character which renders it effective upon gas charges which cannot be exploded by the usual momentarily delivered spark or flash common to ignition systems as heretofore used. There is no self-induced or reactional current, appreciably set up in the coil 22 upon opening of its circuit, but instead such current ceases almost instantly upon the opening of the interrupter terminals, with practically an entire absence of destructive sparking, and a condenser is, therefore, not necessary.

It is obvious that many changes in my invention will occur to one skilled in the art. For example, aside from the modifications above set forth, the generator may be one having permanent magnets and the armature of the same may be of the usual H-type. It is understood that such changes and modifications may be made as fall within the limits of the appended claims.

As stated above, my invention is not limited to ignition systems, as it may find embodiment in other devices such as systems for wireless telegraphy.

Having thus described my invention, what I claim and desire to secure by Letters Patent is:

1. A source of energy and a circuit therefor, a coil inductively related thereto, means for short circuiting said coil, and a second coil inductively related to the first coil and having a spark gap in circuit therewith.

2. A source of energy and a circuit therefor, a coil inductively related thereto, a second coil inductively related to the other coil, and means comprising an interrupter for short circuiting said first coil.

3. The combination with a source of energy and a circuit therefor, a coil inductively related to said circuit and a second coil inductively related to the other coil, of means for intermittently short circuiting said first coil.

4. The combination with a source of energy and a circuit therefor, and a plurality of windings inductively related thereto, of means comprising said source and one of said coils, for causing a discharge of high tension current in another of said coils and following the same by low tension current inductively derived from said source.

5. The combination with a source of alternating current, and a transformer provided with a plurality of windings one of said windings being connected to said source, a circuit comprising a second of said windings and a spark gap, and means for intermittently short circuiting a third of said windings.

6. A source of electrical energy and a circuit therefor, a coil, and means, comprising a second coil, for bringing the first coil into and out of inductive relationship with the said circuit.
7. A source of electrical energy and a circuit therefor, a coil, and means, comprising a coil and make and break mechanism, for bringing the first coil into and out of generative inductive relationship with the said circuit.
8. A source of electrical energy and a circuit therefor, a coil having a spark gap in circuit therewith, and means, comprising a second coil, for bringing the first coil into and out of inductive relationship with the said circuit.
9. A source of electrical energy and a circuit therefor, a plurality of coils subject to inductive influence of said circuit, one of said coils having a spark gap in circuit therewith, and means for controlling the latter coil with respect to the spark gap, and comprising another of said coils.
10. A source of electrical energy and a circuit therefor, a coil in circuit therewith, a second coil, and means comprising a circuit independent of the first circuit, for bringing the second coil into and out of inductive generative relationship with the first coil.
11. A source of electrical energy and a circuit therefor, a primary coil in circuit therewith, a secondary coil, and means comprising a third coil, for controlling inductive relationship of the second coil with the primary coil.
12. A source of electrical energy and a circuit therefor, a primary coil in circuit therewith, a second coil, and means comprising a third coil and interrupter mechanism in circuit therewith, for controlling inductive relationship of the second coil with the primary coil.
13. A source of electrical energy and a current circuit therefor, a coil in circuit therewith, a second coil inductively related to the first coil and having in circuit a spark gap, and means, including an independent circuit, for building up from said source energy in said first coil and for transferring said energy to the second coil to cause a spark across said gap.
14. A source of electrical energy and a circuit therefor, a primary coil inductively associated therewith, a second coil having in circuit a spark gap, and a third coil for controlling the second coil, and having a circuit independent of the primary coil.
15. A source of electrical energy, a primary coil inductively associated therewith, a second coil having in circuit a spark gap, and a third coil having in circuit interrupter mechanism; the circuit of the last named coil being independent of the primary coil.
16. A source of electrical energy, a primary coil and a secondary coil having a spark gap in circuit therewith, and means, including an independent circuit and controlling mechanism for building up from said source energy in said primary coil and for transferring said energy to the secondary coil to cause a spark across the gap.
17. A source of electrical energy, a secondary coil having a spark gap in circuit therewith and a primary coil, and common means, including an independent circuit, for building up from said source energy in said primary coil, for transferring said energy to said secondary coil to produce an initial high tension discharge across said gap, and for following the initial discharge by a low tension discharge.
18. A source of current and a coil connected thereto, a plurality of coils inductively related to said coil, and means, comprising a core and controlling mechanism, for building up from said source energy in one of said coils and for transferring said energy to another of said coils and at the same time supplying energy from said source.
19. A coil having a spark gap in circuit therewith, a second coil inductively related to the other coil and a third coil, means, comprising a source of current, for building up energy in the third coil, and means for transferring said energy to the first coil, said means including the second coil and circuit controlling means therefor.
20. A source of electrical energy and a circuit therefor, a plurality of windings inductively related thereto, and means, comprising said source and one of said coils, for causing a discharge of current in another of said coils and sustaining said discharge by a flow of current inductively derived.
21. A transformer provided with a plurality of windings one of which is for connection with a source of electrical energy, a circuit comprising a second one of said windings and a spark gap, and means for intermittently closing and opening the circuit of a third one of said windings.
22. The combination with a stationary magnetizable core, of means for producing an alternating flux therein, means for causing a leakage of said flux, and a circuit comprising a spark gap and a coil upon said core.
23. The combination with a stationary magnetizable core, and means for producing an alternating magnetic flux therein, of means for diverting of a portion of said flux through a leakage path, and means for utilizing the transfer of said flux to its normal path to produce an electric spark.
24. A stationary magnetizable core, means, including a current circuit, for producing

an alternating magnetic flux therein, two circuits similarly subject to the influence of said flux, and a current using instrumentality located in one of said circuits and 5 means for interrupting the other of said circuits.

25. A transformer core, a coil for setting up from an electrical source a magnetic flux therein, a second coil having a spark gap, 10 and a choke coil associated with the transformer core and adapted to control the flux thereof with respect to the second coil.

26. A transformer core, a coil for setting up from an electrical source a magnetic 15 flux action therein, a second coil subject to inductive influence of the core, and a third coil for controlling the flux action of the core, whereby the second coil may be intermittently energized.

20 27. A transformer core, a coil for setting

up from an electrical source energy in the core, a second coil subject to inductive influence of the core and a third coil for controlling the transformer core with respect to the second coil, whereby the second coil 25 may be energized by said stored energy.

28. A magnetizable core, a coil carried thereby, means, comprising a second coil, for so storing from an electrical source energy in the core as to hold it out of inductive relationship with the first coil and for supplying said energy to the first coil, and interrupter mechanism for controlling the second coil.

In testimony whereof I have hereunto set 35 my hand.

RICHARD VARLEY.
